US00D968512S

(12) **United States Design Patent** (10) **Patent No.:** **US D968,512 S**
Rodgers et al. (45) **Date of Patent:** **** Nov. 1, 2022**

(54) **STORAGE CLIPBOARD**

(71) Applicants: **Bryan Rodgers**, Albuquerque, NM (US); **Chelsey Rodgers**, Albuquerque, NM (US)

(72) Inventors: **Bryan Rodgers**, Albuquerque, NM (US); **Chelsey Rodgers**, Albuquerque, NM (US)

(**) Term: **15 Years**

(21) Appl. No.: **29/741,710**

(22) Filed: **Jul. 15, 2020**

(51) LOC (13) Cl. **19-02**

(52) U.S. Cl. **USPC D19/88**
